(57) **CLAIM**

The ornamental design for a wireless speaker, as shown and described.

DESCRIPTION

FIG. 1 is a front view of the wireless speaker;
FIG. 2 is a rear view of the wireless speaker of FIG. 1;
FIG. 3 is a left or right side view of the wireless speaker of FIG. 1;

FIG. 4 is a top view of the wireless speaker of FIG. 1; and,
FIG. 5 is a bottom view of the wireless speaker of FIG. 1.
Solid lines that extend over stippling are wire frame lines
that indicate contour or changes in plane/curvature.

The stippling illustrates the claimed areas. The non-stippled
areas illustrate the areas that do not form part of the claimed
design.

The dash-dot lines shown in FIGS. 1, 2, and 4 illustrate the
boundary of the claim and form no part of the claimed
design.

The portions of the wireless speaker shown in broken lines
form no part of the claimed design.
